UNITED STATES PATENT OFFICE.

FRED M. PAGE, OF SWAMPSCOTT, MASSACHUSETTS.

COMBINED WAISTBAND, STAY, AND DROP-CURTAIN.

1,202,211.

Specification of Letters Patent.

Patented Oct. 24, 1916.

Application filed April 12, 1915. Serial No. 20,774.

To all whom it may concern:

Be it known that I, FRED M. PAGE, a citizen of the United States, residing at Swampscott, in the county of Essex and State of Massachusetts, have invented certain new and useful Improvements in Combined Waistbands, Stays, and Drop-Curtains; and I do hereby declare the following to be a full, clear, and exact description of the invention, such as will enable others skilled in the art to which it appertains to make and use the same.

This invention relates to a combined waist band, stay and drop curtain for use in the manufacture of trousers and similar articles of apparel.

In the manufacture of trousers it is customary to put a waist band and a stay in the waist of the trousers to hold up the waist and cover up the seams and rough edges and act as a button stay at the top of the trousers. In placing the waist band in the trousers the rough edge of the cloth at the top of the waist is united with a strip of canvas and the canvas folded over inside the trousers. After these are sewed together the canvas and the rough edge of the trouser cloth is then covered with a waist band which may extend down far enough to cover the waist line seams and the stitches for attaching belt loops, or a drop curtain may be attached to the bottom of the waist band to cover these seams. With this and similar constructions, several strips of material are separately fitted and attached while inserting the waist band, requiring three or four machine seams and several hand stitched seams.

The primary object of the present invention is to provide a combined waist band, stay and drop curtain for the waists of trousers which can be prepared in lengths appropriate for all sizes of trousers and adapted to be quickly united as one piece in the trouser waist while giving a neat appearance and the proper shape and body to the waist.

With this object in view a feature of the invention contemplates the provision of a stay or stiffener united by a seam with one edge of a waist band strip and a drop curtain strip, so that the waist band strip may fold over to cover the stay and the uniting seam, and provide a free edge by which the article may be united in the waist of the trouser.

Other features of the invention will be apparent to those skilled in the art from the following detailed description and the accompanying claims.

The preferred form of the invention is illustrated in the accompanying drawings in which—

Figure 1 is a perspective view of the waist of a pair of trousers embodying the preferred form of the invention; Fig. 2 is a rear elevation of the combined waist band, stay and drop curtain, and Fig. 3 is a sectional elevation of the combined waist band, stay and drop curtain taken on the line X³ 70 of Fig. 2.

In the illustrated embodiment of the invention, the combined waist band, stay and drop curtain as an article of manufacture consists of a stay strip 10, a waist band strip 12, and drop curtain strip 14 all united to form one piece. The stay strip may be made of any suitable material such as filled drill, stiff canvas or the like, which acts as a support to give body or stiffness to the waist 20 of the trousers. The waist band strip and drop curtain strip may be of any suitable lining cloth such as drill, sateen, silk, etc.

In making the combined waist band, stay and drop curtain, a uniting edge 16 of the 35 waist band 12 is lapped over the edge of the stay 10. The drop curtain strip is folded upon itself so that the raw edges come together and these edges are placed upon the waist band to approximately register with 90 the uniting edge 16. A line of stitches 18 is then placed close to the edges of the three assembled members to unite them together. The waist band strip is then folded back over the face of the stay strip and is wide 95 enough so that its free edge 20 will project a short distance beyond the free edge 22 of the stay. The combined waist band, stay and drop curtain manufactured in this way is then cut into lengths suitable for trousers 100 so that it can be placed in the trousers without any trimming or fitting.

In placing the combined waist band, stay and drop curtain in the waist of a pair of trousers, its face or waist band side is placed 105 against the outside face of the trouser cloth 26 with the raw edge of the trouser cloth in register with the free edge 20 of the waist band. They are then united by a line of stitches 28 and the combined waist band, stay and drop curtain is folded over with 110 the edge 22 of the stay as an axis so as to

bring the edges 30 united by the seam 28 between the stay 10 and the cloth 26. This edge is then pressed down and the lower edge of the drop curtain 14 is tacked by sets 5 of stitches 32 to the inside linings such as the pockets 34 to hold it in place. The free ends of the combined waist band, stay and drop curtain are stitched to the fly opening of the trousers. With this construction the 10 seam uniting the combined waist band, stay and drop curtain to the trousers and the line of stitches connecting the waist band, stay and drop curtain are concealed, which tend to give a neat appearance to the 15 trousers. Further, with this form of connection, the combined waist band, stay and drop curtain can be united quickly and easily in the trousers and when in place will give the waist the desired rigidity or stiffness and hold the shape of the waist in the 20 trousers.

This combined waist band, stay and drop curtain constitutes a garment part which is adapted conveniently and easily to be incorporated 25 into the garment and there to discharge the duties for which it is intended in a highly efficient, satisfactory and durable manner. Thus the part, when incorporated in a pair of trousers, forms a stiffening for 30 the waist of the trousers and maintains the shape of the waist. It is convenient for use in the manufacture of the trousers and contributes to shorten the length of time required in the manufacture, and therefor to 35 reduce the cost. The construction commends itself to the garment part manufac-

turer by reason of the fact that it is inexpensive to make, inasmuch as only one labor operation is required to be performed upon the article in the process of its manufacture, 40 namely, the sewing of the seam by which the waist band, the stay and drop curtain are united.

Having thus described the invention, what is claimed is:

1. A combined waistband, stay and drop curtain for garments, comprising a stay strap, a lining strap covering one side of said stay strap and having its lower edge folded around the lower edge of said stay 50 strap and stitched thereto adjacent said lower edge and with its upper edge extending beyond the upper edge of the stay strap to form a free edge adapted for engagement with the garment, and a drop curtain strip 55 folded upon itself and having its contacting longitudinal edges secured to said stay and lining strips by the stitching which secures the stay and lining strips together.

2. A combined waistband, stay and drop 60 curtain for garments, comprising a stay strip, a lining strip having one edge secured to the lower edge of said stay strip in overlapping position and of sufficient width to enable it to be folded around said lower 65 edge of the stay strip and completely cover one face of the stay strip and project beyond the upper edge thereof to form a free attaching edge, and a drop curtain strip secured against the overlapping edge of the lining 70 strip.

FRED M. PAGE.
